W. F. DUNLOP

DENTAL CHUCK

Filed March 20, 1926

William F. Dunlop
INVENTOR

BY *Victor J. Evans*

ATTORNEY

WITNESS *J. L. Wright*

UNITED STATES PATENT OFFICE.

WILLIAM F. DUNLOP, OF NEW YORK, N. Y.

DENTAL CHUCK.

Application filed March 20, 1926. Serial No. 26,329.

This invention relates to improvements in chucks for dental instruments, the general object of the invention being to provide means for frictionally holding the bits or burrs in the rotary member or chuck of the drilling apparatus and in such a manner that the bit can be easily removed.

This invention also consists in certain other features of construction and in the combination and arrangement of the several parts, to be hereinafter fully described, illustrated in the accompanying drawings and specifically pointed out in the appended claims.

15 In describing my invention in detail, reference will be had to the accompanying drawings wherein like characters denote like or corresponding parts throughout the several views, and in which:—

20 Figure 1 is a view partly in section, showing a portion of a drilling apparatus with the improvement thereon.

Figure 2 is a view of the chuck or rotary member, with parts in section, showing a 25 drill therein.

Figure 3 is a sectional view of the lower end of the chuck.

Figure 4 is a view of a bit.

30 Figure 5 is an enlarged sectional view showing a bit in the chuck.

Figure 6 is a section on line 6—6 of Figure 5.

As shown in these views, I make the bore of the chuck or rotary member 1 of the drilling apparatus of two diameters, the inner part 2 being of less diameter than the outer part 3 so that a small shoulder 4 is formed at the junction of the two parts. This shoulder is slightly tapered, as shown. The bit 5 used with this device is provided with a slot 6 in its chuck engaging end which makes this end of the bit forked, the prongs being resilient so that as the bit is pushed into the bore, it will slide freely through the large part 3 until it strikes the shoulder 4, when the prongs will be pressed together by the shoulder so that the extremities of the prongs will enter the small part 2 and thus the bit will be firmly and securely held in the chuck. However, the bit can be easily pulled from the chuck when it is to be re-

55 moved, as the prongs will give inwardly under the pulling strain and thus permit the bit to easily pass from the small part of the bore.

The member 1 is carried in the usual handle part 7 of the drilling apparatus and has its reduced end 8 passing through the arm 9 of the apparatus, the projecting part receiving the pulley 10 which receives the 60 belt from the motor, these parts being held assembled by the nut member 11.

From the foregoing, it will be seen that I have provided simple and inexpensive means for firmly and securely holding a bit in a 65 chuck and in such a manner that the bit can be drawn from the chuck with but little effort.

While the improvement is mainly intended for dental apparatus, it will, of 70 course, be understood that it can be used on other apparatus.

It is thought from the foregoing description that the advantages and novel features of my invention will be readily apparent.

I desire it to be understood that I may make changes in the construction and in the combination of the several parts, provided that such changes fall within the scope of the appended claims.

80 What I claim is:—

1. In combination with a chuck having a bore of two diameters with the large part of the bore opening out at the end of the chuck, a removable bit having resilient prongs for 85 entering the bore, the prongs being pressed together when they enter the small part of the bore.

2. In combination with a chuck having a bore of two diameters with the large part of the bore opening out at the end of the chuck, the two parts forming a shoulder at their junction, a removable bit having a slot in its chuck engaging end which forms a pair of resilient prongs which are pressed toward 90 each other by the shoulder when the bit is forced into the chuck so that the prongs will enter the small part of the bore.

95 In testimony whereof I affix my signature.

WILLIAM F. DUNLOP.
